UNITED STATES PATENT OFFICE

ALDEN E. FINLEY, OF KITTERY, MAINE, ASSIGNOR TO ELECTRIC BOAT COMPANY, OF GROTON, CONNECTICUT, A CORPORATION OF NEW JERSEY

SAFETY DEVICE

Application filed September 29, 1928. Serial No. 309,166.

This invention relates to safety devices, and more particularly to a device especially adapted for use with submarine boats.

It frequently occurs that, due to weather conditions or other causes, unavoidable delay is encountered in effecting the rescue of the men from a submarine boat which has been disabled by collision or from other causes, and is submerged at an appreciable depth. This delay may prove fatal to the men in the disabled boat due, chiefly, to the limited air supply available. In such cases, the lives of the men could be sustained until rescue was effected by providing a suitable supply of fresh air, primarily, and nourishing food. My invention has to do particularly with means incorporated into the submarine boat as a part of the structure thereof, such means rendering it possible to supply fresh air, food, and other necessities to the occupants of the disabled boat. It is also possible, by my invention, for the occupants of the disabled boat to communicate directly with persons exterior of the boat in the event that other means of communication are not readily available. The device of my invention is so associated with the hull of the boat as to serve, in a supplemental capacity, to reinforce the same. A further advantage of my invention is the possibility of releasing, from within the boat, signal buoys and self lighting flares. My invention also renders it possible to connect to the interior of the boat various appliances for salvage and other purposes, and to expel waste products from within the disabled boat. Further objects and advantages of my invention will appear from the detailed description.

In the drawings:

Fig. 1 is a view in side elevation of a submarine boat having safety devices constructed in accordance with my invention applied thereto;

Fig. 2 is a fragmentary sectional view through the hull of the boat showing the device as applied and illustrating the manner of removal of the outer closure cap;

Fig. 3 is a sectional view through the hull and the device applied thereto, on an enlarged scale; parts being shown in elevation;

Fig. 4 is a fragmentary sectional view through the device at the outer end thereof showing the interlock and signal means;

Fig. 5 is an outer end view of the device as applied;

Fig. 6 is an inner face view of the inner closure cap;

Fig. 7 is a plan view of a modified form of my invention, as applied;

Fig. 8 is a vertical sectional view through the device of Fig. 7; and

Fig. 9 is a vertical sectional view through a second modified form of my invention as used in connection with air hose.

My invention is particularly adapted for use with a submarine boat B of the double hull type including an inner hull 1 and an outer hull 2, though it is not limited to this one use as it can also be readily applied to boats of single hull construction. In accordance with my invention, I provide a cylindrical tubular member 3 which extends through the hulls 1 and 2 and is open at both ends. This member is closed at its outer end by a cap 4 which screws onto the member 3 and forms a water tight closure therewith. The inner end of member 3, which opens into a compartment of the boat, is closed by a cap 5 which, like cap 4, screws onto the end of member 3 and forms a water tight closure therewith. Member 3 is provided, adjacent its outer end, with an integral radial flange 6 which is secured to hull 2 by rivets 7 or in any other suitable manner. A flange ring 8 is screwed upon the inner end portion of member 3 into contact with the inner face of hull 1 to which it is secured by rivets 9, or in any other suitable manner. I thus provide a cylindrical tubular member which opens interiorly and exteriorly of the hull of the boat and is provided at its ends with removable water tight closure members.

Cap 4 is provided, at its outer face, with an air connection in the form of a threaded nipple 10, the bore of which extends through the cap 4 by a duct 10a. This nipple receives a closure cap 11 screwed thereon and serving to form a water tight closure of the outer end of the nipple. This cap is provided with a diametrically extending rib 12 having an

opening 13. This rib provides means for threading the cap onto or off of the nipple by inserting a suitable instrument through the opening or eye 13 or by grasping the rib 12 in a suitable manner. The cap 5 is provided on its inner face with an air connection in the form of a nipple 14 opening through the cap 5 by means of a duct 15. This nipple is similar to the nipple 10 of cap 4 and receives a closure cap 16 similar to cap 11. It will be noted that the cap 16 of the air connection 14 is disposed so as to be accessible exteriorly of the hull. By removing the cap 4 access may be had to cap 16 which may be removed by the diver, under certain conditions to be more fully explained, so that by connecting an air hose to the air connection or nipple 10, after the cap 4 has been replaced, air under pressure may be supplied to the compartment of 20 the boat into which the member 3 opens.

The tubular member 3 receives a cylindrical container 17 of a diameter to be readily inserted into and withdrawn from the tubular member and to occupy substantially the full 25 interior space thereof. This container is closed at one end and is provided at such end with an eye 18. At its other end, the container is closed by a suitable cap 19 screwed onto the end of the container, which is reduced and exteriorly threaded for this purpose. This cap forms a removable air tight and water tight closure for the other end of the container. A suitable gasket may be associated with the cap for assuring the 35 proper closure of the container in such manner as to effectively eliminate possibility of entry of moisture thereinto. This cap or closure member 19 is provided with an eye 20 similar to the eye 18. These eyes are adapted for reception of lines inserted thereinto for 40 raising and lowering the container to and from the surface.

In practice, I provide two tubular members 3 for each of the compartments of the boat, these members being disposed at opposite sides of the hull so that, in the event the hull is resting on its side in such a position as to render the devices at one side thereof inaccessible, the devices at the other side of the hull can be utilized to render assistance to the men in the disabled boat. Normally the container 17 remains within the tubular member 3 and, preferably, this container has disposed there-in suitable supplies such as might be required by the men in the boat, such as emergency rations, oxygen, and medical and surgical supplies. In the event of the boat becoming disabled through collision or other cause, the men within the compartment remove the inner cap 5 and withdraw the container 17 therefrom, and then remove the contents of the container. After this has been done, the ranking man in the compartment, who assumes command, writes out a list of men and a report of the accident, giving whatever in-

formation is necessary in effecting rescue work. If the men in the compartment are in need of immediate assistance in some particular respect, as, for instance, if air is required, this fact is stated in writing on the exterior 70 of the container, which is provided with a portion 17^a of its exterior surface which is sanded, or treated in any other suitable or preferred manner, so as to be readily written upon. The container is then tightly closed 75 by the cap 19 and is replaced in the tubular member 3, the closure cap 5 being then screwed tightly onto the inner end of member 3. The diver then removes the cap 4 by means of a bar 21 (Figure 2) or other suitable implement inserted between a pair of segmental lugs 23 provided on the outer face of cap 4 for this purpose. The cap 5 is provided with similar lugs 23^a adapted for cooperation with a bar or other implement for screwing this cap onto and off of the inner end of the tubular member 3. After removing the cap 4, the diver withdraws the container 17 and inspects the exterior thereof carefully to see if there is any message requesting immediate aid in any particular with which the diver is able to comply such as, for instance, a request for air. The container is then hooked onto a suitable line and drawn to the surface vessel from which the diver operates, where it is opened 90 and the statement within the container is read enabling the rescue work to be conducted in the most advantageous manner. The supplies which may have been requested by the men in the compartment of the disabled boat are then placed in the container which is closed by the cap 19 and lowered to the diver who inserts it into the tubular member 3 and then replaces the cap 4, screwing it tightly onto the outer end of the tubular member 100 to form a water tight closure therewith. The occupants of the compartment of the boat then remove the cap 5 and withdraw the container from the tubular member 3, after which the container is emptied and is replaced in the tubular member in the manner described. This provides simple and highly efficient means whereby the men in the compartment of the disabled boat can receive necessary supplies and can communicate with persons exterior thereof. 105

As will be readily apparent it is, of course, essential that the cap 5 at the inner end of the tubular member 3 be not removed while the cap 4 is removed from the outer end of such member. To eliminate this possibility due to confusion in signals or other causes, I provide suitable interlock and signalling means whereby the removal of the cap at either end of the tubular member 3 is prevented when the cap at the other end of this member is removed. Referring more particularly to Figures 3 and 4, I provide two rods 24 which are slidably mounted through suitable bores in the wall of member 3, from 110 115 120 125

opposite ends thereof. Member 3 is provided, at each end, with a recess 25 in the form of a narrow slot in which operates an indicating and locking member 26 which is rockably mounted on a pin 27 extending transversely of the slot 25. This pin is provided with an angularly disposed finger 28 which contacts with the adjacent end of the rod 24. A wire spring 29 is disposed about the pivot pin 27 and has one arm bearing on the finger 28, the other arm of this spring bearing against a stop pin 30 extending transversely of the slot. The finger 28 bears against an enlarged head 24a at the adjacent end of rod 24, this head seating in a recess 31 forming a continuation of the slot 25 when the rod 24 is released and the member 26 is raised into locking position. The locking member cooperates with a plurality of locking lugs 32 projecting inwardly from the inner face of the adjacent cap. The rods 24 are of such length that, when the caps 4 and 5 are turned onto the member 3 into full closed position, the heads 24a of the rods contact with the fingers 28 and swing the locking members 26 downwardly into inoperative position within the recesses or slots 25 as illustrated in full lines in Figure 4. Each closure cap is provided with a window in the form of a pane or block of glass 33 of suitable thickness to withstand the high pressure to which it is subjected, this block being suitably set into the cap. Block 33 is disposed in alignment with an opening 34 in the cap so arranged that when the cap is screwed into its full operative position upon the tubular member 3, locking member 26 will be in alignment with the opening 34. The edge of the locking member adjacent the cap 4 is preferably coated with a suitable luminous substance so as to be readily visible through the glass 33. Under normal conditions, with both of the closure caps in position, the locking members 26 are in depressed or inoperative position so that either cap can be removed. If, in example, the inner cap 5 is removed, the rod 24 which contacts with this cap is released permitting the member 26 to be moved upwardly or inwardly of member 3 by its associated spring 29 into substantially the dotted line position of Figure 4. When in this position, the member 26 is disposed in the path of the adjacent lug 32 of cap 4 and serves to effectually prevent removal of this cap. By glancing through the glass 33, the diver can readily determine whether the cap 5 at the inner end of the tubular member has been removed as removal of this cap is indicated by the absence of the luminous edge of member 26 from in back of the glass 33, replacement of the cap being indicated by the luminous edge of member 26 being visible through the glass 33. In the same manner, the occupants of the compartment into

which the tubular member 3 opens can readily determine whether the cap 4 at the outer end of this member is in position or not, and removal of cap 5 before the cap 4 has been replaced is prevented. Any other suitable or preferred interlock and indicating means may be employed and I do not wish to be limited in any way to the particular means set forth herein.

In the event that the occupants of the compartment are in urgent need of air, the diver after removing the container 17, replaces the cap 4. He then removes the cap 11 from the outer air connection or nipple 10 and screws onto this nipple a connecting member of an air hose extending from the ship at the surface, air being supplied to this hose under pressure in a known manner. If desired, the diver's air line may be provided with suitable means for connecting the same to the nipple 10, as is well understood in the art. After the connection has been made to the nipple 10, the diver signals this fact to the occupants of the compartment who then remove the cap 5, permitting the water in the member 3 to drain into the compartment. The air supplied under pressure to the nipple 10 flows into the member 3 and thence into the compartment of the disabled boat. After a sufficient supply of air has been forced into the compartment to insure the safety of the men therein, the air connection may be discontinued and the member 3 may be used as before for conveying supplies to the men within the submarine. In the event that a compartment has two of these devices available for use, one of them can be used for conveying supplies to the compartment and the other can be utilized for supplying fresh air to the compartment, as will be readily understood.

In practice, the diver after reaching the disabled boat, moves along the boat and strikes the hull with a hammer at short intervals. When his signals are answered from a compartment, he proceeds as above described, to render aid to the occupants thereof. In the event that he receives no response from a compartment, he may connect an air line to such compartment to blow it out for salvage purposes. To accomplish this, the cap 4 is removed and the container 17 is withdrawn from the member 3, after which the cap 16 is removed from the inner nipple or air connection 14 and the closure cap 4 is then replaced. Cap 11 is then removed from the nipple 10 and the air line is connected to this nipple, as described. Air is then forced through nipple 10 and duct 10a into member 3 from which it passes through the nipple 14 and duct 15 into the compartment. In the event that there are survivors in this compartment, who, due to weakness or other cause, resulting from bad air, were unable to answer the diver's sig-

- nals, the supply of fresh air to this compartment will serve to revive such survivors, who can then signal to the diver. The diver's first duty is, of course, to render all assistance possible to the survivors in the disabled boat. After this has been done, any flooded compartments may be blown out to assist in salvaging the boat and facilitate rescue of the survivors therein.
- 10 In the modified form illustrated in Figs. 7 and 8, I have provided a tubular member 35 formed of two sections 36 and a coupling sleeve 37 fitting about such sections and secured thereto by welding. The tubular member may be provided with a suitable liner, though this is not essential. Each of the sections 36 is carried by, and preferably formed integrally with, a plate 38 or 39. Plate 38 is riveted or otherwise suitably secured to the inner face of hull 40 at the top thereof. This plate carries two bearing sleeves 41 which project through openings 42 in the hull. Plate 38 is also provided with stuffing boxes 43 on its inner face, aligned with sleeves 41. The outer plate 39 is secured to the bottom wall 44 of a boxing or depression 45 formed in superstructure 46 and normally covered by a removable plate 47.
- 20 Plate 39 is provided, in its upper face, with two bearing sleeves 48 and 49 which are aligned with sleeves 41. An operating shaft 50 is rotatably mounted through sleeve 49 and the aligned sleeve 41 and stuffing box 43 of plate 40. A second shaft 51 is rotatably mounted through sleeve 48 and the other sleeve and stuffing box of the inner plate. A worm 52 is secured on shaft 50 and meshes with a gear segment 53 pivoted at 25 54 between two parallel ribs or flanges 55 connecting sleeve 49 and tube section 36 of plate 39. Gear segment 53 is formed integrally with, or otherwise suitably secured to a cover 56 for closing the outer end of the tube. The worm 52 is confined between sleeve 49 and the bight portion 57 of an inverted U-shaped bracket 58 secured to the upper face of plate 39 and straddling sleeve 49. A stop collar 59 is secured on shaft 50 and contacts the upper face of element 57. The shaft is thus held against endwise movement in either direction. The shaft is turned in desired direction either from within or without the compartment of hull 40 by means of hand wheels 60 secured on the ends of the shaft. Shaft 51 is held against endwise movement in the same manner as shaft 50, and is provided with hand wheels 60 and a worm 52 secured thereon.
- 30 Worm 52 of shaft 51 meshes with gear segment 53 which carries cover 56 for the inner end of the tube, this gear segment being pivoted at 54 between ribs or flanges 55 connecting stuffing box 43 and the inner tube section 36.

By means of the shafts and associated gear, the cover at either end of the tube can be opened either interiorly or exteriorly of the hull. The tube structure preferably connects the hull and the superstructure, as illustrated. This has the advantage of providing firm and level footing for the divers, and avoids the great handicap incident to working in the mud or from a swinging scaffold at the side of the disabled submarine. Placing the tube structure at the top of the compartment also renders it feasible to release small buoys and self igniting signals or flares from the disabled boat, by proper manipulation of the covers. Whether the cover at the inner end of the tube is closed, can be readily determined from the exterior of the hull by turning shaft 51 in cover closing direction. In the same manner, the occupants of the compartment in hull 40 can determine whether the outer cover is closed. If the inner cover is not closed, the diver should close it before opening the outer cover, and the occupants of the disabled boat should close the outer cover, if open, before opening the inner cover.

In the form of Figs. 7 and 8, the tube is formed of three members, the two sections 36 and the coupling 37. This is advantageous, as the length of the tube structure can be varied to suit the distance between the superstructure and the hull of the particular boat to which the device is applied. The device may thus be standardized so as to be readily applied to present day submarine boats of different types. This device may also be applied to double hulled boats, and I do not intend to in any way limit its use to single hull boats.

The modified form of Fig. 9 employs a tube 61 carried by a plate 62 riveted, or otherwise suitably secured, to the hull 40. A cover 63 is pivoted at 64 between a pair of arms 65 extending from the inner end of the tube. A gear segment 66, rigid with the cover, meshes a worm 67 secured on a shaft 68 rotatably mounted through a stuffing box 69 and bearing sleeve 70 of plate 62, this shaft also extending through a bearing sleeve 71 secured to the under face of superstructure 72. Hand wheels 73 are secured on the ends of shaft 68. By rotating the shaft in the proper direction the cover can be moved into either open or closed position either exteriorly or interiorly of the hull.

Tube 61 is provided, at its outer end, with an exteriorly threaded shoulder 74 upon which are threaded clamping rings 75 at opposite faces of the deck of superstructure 72, these rings serving to securely clamp the outer end of the tube to the superstructure. The shoulder 74 normally receives a screw cap similar to that of Figs. 1 and 2, for closing the outer end of the tube. This shoulder is also adapted to receive an interiorly threaded

ring 76 of a coupling 77 secured on one end of a hose pipe 78 which may extend from a rescue ship on the surface, or from a rescue submarine boat below the surface. Coupling 77 carries an inner tube 79 suitably supported in concentric relation to hose pipe 78, and an inner hose pipe 80 is suitably connected to the upper end of this tube. A tube 81 is suitably mounted in the lower end of the tube 79 to provide a slip joint so that the cover 63 can be closed, if required, while the hose is connected to the tube 61.

With the hose pipe 78 connected to tube 61, fresh air can be supplied to the compartment within hull 40 through hose 80 and tubes 79 and 81, the foul air passing out through tube 61 and hose pipe 78. A tube or hose can be connected to tube 79 or tube 81, if desired, to admit the fresh air at any desired location in the compartment, though ordinarily this may not be necessary. Obviously, a hose pipe connected to the tube 61 may be used for many other purposes, such as a speaking tube, for conducting supplies to the interior of the disabled boat, providing pumping connections or apparatus for lowering the water level in the compartment, etc. I also contemplate providing the tube illustrated in Figs. 7 and 8 with either interior or exterior threads, at its outer end, whereby a hose pipe, or other appliance having a suitable coupling member, can be quickly coupled to the tube.

The coupling ring 76 is preferably provided with arms 82 projecting radially therefrom. These arms provide grips or hand holds which enable the diver to turn the ring tightly onto, or remove it from, the tube without the use of tools.

When the disabled boat is equipped with the apparatus of Figs. 7 and 8, or of Fig. 9, it is not necessary that the diver first signal the occupant of a compartment by signaling. He can readily determine, by means of the hand wheels, in which compartments the inner covers of the tubes are closed. His first duty is to remove the containers from such tubes, examine them for writing, and then send them to the rescue boat or ship. After the needs of the survivors in the disabled boat have been attended to the diver may open the outer covers of the tubes leading to the flooded compartments and then connect air lines to such tubes to blow out such compartments for rescue or salvage purposes, after which he opens the inner covers of these tubes.

While I have described my device as used in connection with rescue operations conducted from a surface ship, it is equally well adapted for use in such operations conducted from a submerged ship, such as a rescue submarine such as that disclosed in the pending application of Lawrence Y. Spear, filed February 20th, 1928, Serial No. 255,684.

In either case, my device provides simple and highly efficient means whereby men entrapped in a disabled submarine boat can be provided with fresh air and other necessary supplies from the exterior of the boat so as to be kept alive until their rescue can be effected.

What I claim is:

1. In a submarine boat, in combination, a tubular member having one end opening exteriorly of the hull and its other end opening interiorly of the hull, removable water tight closure members for the ends of said member, air connections at the ends of the tubular member, and closures for said connections removable exteriorly of the hull.

2. In a submarine boat, in combination, a tubular member having one end opening exteriorly of the hull and its other end opening interiorly of the hull, removable water tight closure members for the ends of said member, an air connection opening through the inner closure member, and removable means accessible exteriorly of the hull for closing said connection.

3. In a submarine boat, in combination, a tubular member having one end opening exteriorly of the hull and its other end opening interiorly of the hull, closure caps removably secured on the ends of said member, air connections carried by and opening through the respective caps, and removable means accessible exteriorly of the hull for closing said air connections.

4. In a submarine boat, in combination, a tubular member having one end opening exteriorly of the hull and its other end opening interiorly of the hull, removable covers for the ends of said member, and means operable both exteriorly and interiorly of the hull for opening and closing the covers.

5. In a submarine boat, in combination, a tubular member having one end opening exteriorly of the hull and its other end opening interiorly of the hull, removable covers for the ends of said member, and means operable both exteriorly and interiorly of the hull for opening and closing the inner cover, said means also serving to indicate exteriorly of the hull whether the inner cover is closed.

6. In a submarine boat, in combination, a tubular member having one end opening exteriorly of the hull and its other end opening interiorly of the hull, removable covers for the ends of said member, and means operable both exteriorly and interiorly of the hull for opening and closing the covers, said means also serving to indicate whether the interior or exterior cover is closed.

In consideration whereof I hereunto subscribe my name this 20th day of April, 1928.

ALDEN E. FINLEY.
